UNITED STATES PATENT OFFICE.

JOHN F. SANDERSON, OF MINNEAPOLIS, MINNESOTA.

ELEVATOR.

SPECIFICATION forming part of Reissued Letters Patent No. 12,157, dated September 15, 1903.

Original No. 674,473, dated May 21, 1901. Application for reissue filed July 20, 1903. Serial No. 166,410.

To all whom it may concern:

Be it known that I, JOHN F. SANDERSON, a citizen of the United States, residing at Minneapolis, county of Hennepin, and State of Minnesota, have invented certain new and useful Improvements in Elevators, of which the following is a specification.

My invention relates to elevators for the expeditious and economical handling of grain, seeds, and ground substances, as well as for other materials in bulk; and it more particularly relates to portable elevators embodying a series of flights or an equivalent thereof for transferring grain from wagons into bins, grain-cars, or other receptacles, or vice versa; and to that end it consists in the features of construction and combination hereinafter to be more fully described, and pointed out in the claims hereto annexed.

Referring to the accompanying drawings, wherein like reference-letters indicate the same or corresponding parts, Figure 1 is a side elevation of one form of my device. Fig. 2 is a plan view of the form of my apparatus shown in Fig. 1, a small portion being shown in section. Fig. 3 is a sectional view of a portion of the parts shown in Figs. 1 and 2. Fig. 4 is a vertical section taken on the line 4-4 of Fig. 3. Fig. 5 is a plan view, a portion thereof being shown in section, taken on the line 5-5 of Fig. 4. Fig. 6 is a perspective view of the form of my device shown in Fig. 1 when folded for transportation. Fig. 7 is a side elevation of a modified form of a portion of the parts shown in Figs. 1 and 2. Fig. 8 is a plan view of the parts shown in Fig. 7, a small portion thereof on line 8-8 being shown in section. Fig. 9 is a section view of a portion of the parts shown in Fig. 7, taken on the line 9-9 thereof and viewed in the direction indicated by the arrows at the sides of said figure. Fig. 10 is a sectional view on line 10-10 of Fig. 9 viewed in the direction indicated by the arrows at the top and bottom of said figure. Fig. 11 illustrates one manner in which the end c^4 of the conveyer-casing C may be connected to the opening of the elevator-boot, so as to form a continuous passage from the hopper to said boot, as will be hereinafter more fully described. Fig. 12 is a perspective view illustrating a modified form of a portion of the parts shown in Fig. 1 and illus-

trates that form of driving mechanism I prefer to employ in connection with my device. Fig. 13 is an end view of the parts shown in Fig. 12.

I am well aware that portable elevators are well known in the art and that the elevating mechanism of said devices has been operated by various power means. It will therefore be understood that my invention is not limited to the particular character of power and power-transmitting means hereinafter described in connection with my device; nor do I limit my invention to portable elevators, inasmuch as the portability of the device does not form an essential feature thereof, but is rather a mere means for conveniently moving the device from place to place, as desired. It will also be understood that the movability of the device may be accomplished by horse, electric, or steam propelling power, as desired, and that said transporting means may be so connected to the device as to operate the conveying or elevating mechanism when the conveyer is stationary and in position for use, or said operating power means may be separate and distinct from the transporting power means.

Referring to the drawings, A is a casing or jacket containing suitable elevating mechanism connected to the operating power means and indicated in the form shown in the drawings by the letter a. B is an adjustable hopper, hereinafter to be more fully described. C is a casing or jacket, within which and properly connected to the operating power means is a suitable conveying device. Both the elevating and conveying means referred to may consist of any of the well-known devices, such as an endless screw or an endless chain or belt provided with buckets or flights of any suitable form, said conveying means in the form shown in the drawings being indicated by the letter c. The operation of this portion of my device is as follows: Assuming the elevating and conveying devices to be in operation, if grain be cast into the hopper B it will pass through the aperture b at the base thereof into the conveyer-jacket C, whence the conveying mechanism c will communicate it to the elevator-boot a', where it will come into contact with the elevating mechanism a and be finally discharged from the spout a^2 .

Referring to the particular power means illustrated in Figs. 1 and 2, D is a horse-power sweep connected to the master-gear wheel d, which gear-wheel is pivoted on a rocker d', supported on the forward axle J and connected with the rear axle C' by a reach J'. d² is a bevel-gear, the teeth of which intermesh with the teeth of the gear-wheel d. d³ is a main shaft connected to the bevel-gear d² and also connected to the bevel-gear d⁴, which intermeshes with the bevel-gear d⁵. E F are pulleys respectively operating the belts e f, which in turn respectively control the operation of the pulleys E' F' and the conveying and elevating mechanism connected therewith.

Having described the general relation of the parts of the device one to another, I will now more fully describe the parts to which my invention more particularly relates, their functions, and operations.

Again referring to the drawings, the hopper B is, as stated, provided with an aperture at its base b, which opening is controlled by the slide or shutter b', and it is further provided with a flange b², having elongated bolt-holes b³. (Shown in dotted lines, Figs. 5 and 8.) The flange b² rests upon a flange or shelf b⁴, attached to the casing C, said two flanges being secured together by means of the bolts b⁵, which pass through the apertures b³, which are of such shape as to admit of the hopper being laterally or longitudinally adjusted in order to bring it in proper relation with the source of supply, as a wagon-body, grain-car, &c. The frame G, mounted upon the rear axle C', has upright standards C², connected by a cross-rod C³, whereon the upright casing A is hinged and adapted to be swung down to a substantially horizontal position when it is desired to move the apparatus from place to place. The casing C is provided with bracket-rods C⁴, that are hinged on lugs c², provided on said frame, by means of the removable pivot-rods c³, and, together with the hopper mounted thereon and its contained conveying mechanism, may be swung to one side or another, as desired, by removing one of the pivot-rods c³ and (when necessary) the belt f, thereby permitting said parts to be swung upon the other of said pivot-rods. It is necessary to so move the parts referred to before the elevating mechanism can be folded in the manner illustrated in Fig. 6, after which the hopper and other adjustable parts may be returned to their normal position, as also shown in Fig. 6. It will be observed that the open end c⁴ (shown in Fig. 6) of the conveyer-casing C when the parts of the device are in their normal operative position, as shown in Figs. 1, 2, 7, 8, and 9, communicates with a similar opening in the elevator-boot and when the hood or flexible or foldable portion of the feed-passages is employed that a continuous passage exists from the hopper to the elevator-boot, even if the pivotally-adjustable

portions are not in their exact normal position. (See Fig. 11.)

The lateral and longitudinal adjustability of the hopper and the pivotal adjustability of the casing C, the hopper mounted thereon, and the conveying mechanism contained within the casing, which constitutes a forced feed to the elevating mechanism, form in themselves separate and essential features of my invention, as do they also in combination with the power-transmitting and the elevating mechanisms.

Elevators as now known to the art are chiefly defective because the hopper is not adjustable with relation to the source of supply. It is difficult and oftentimes impossible to properly direct into the mouth of the hopper the commodity to be elevated. Especially is this the case when the source of supply is one which in order to unload its contained commodity into the hopper it is necessary to back toward the same or to scoop it therefrom and throw it into the mouth of the hopper, an operation that occasions a great loss of time as well as of material.

Figs. 7 and 8 show a modified form of my device in which the normal position of the pivotally-adjustable parts hereinbefore referred to is at the side instead of at the end of the device, as shown in Figs. 1, 2, and 6.

Figs. 9 and 10 illustrate one of the many well-known forms in which the interior of the elevator-boot may be constructed in order to direct materials received therein to the elevating mechanism.

Figs. 12 and 13 illustrate, as stated, the power-transmitting means I prefer to employ in connection with the other parts of my device. Referring to said figures, d³ is a main driving-shaft which in revolving causes the chain-wheel d⁶ to turn, thereby turning the chain-wheel d⁷, which is connected to it by means of the chain belt d⁸. When the chain-wheel d⁷ is caused to revolve, it turns the pulleys E F, which in turn operate their respective belts e f and the conveying mechanism controlled thereby. When this form of power-transmitting mechanism is employed, the hopper B and the feed-box C are when in position for operation at the side of the device, in the same manner as shown in Figs. 7 and 8.

It is obvious that the elongated bolt-holes b³ may be in either or both of the flange-plates b² b⁴ and that they may be of any suitable number, size, and form; that the delivering member a² may be an open trough or a closed tube or passage and that, if preferred, it may be flexible or telescopic in its action, in which latter form it is shown in the drawings; that the pivotally-adjustable parts may be pivoted or hinged to the device in any suitable manner and at any suitable point; that the hopper B may be of any preferred form and size and that when employed with the pivotally-adjustable feed it may or may not be

independently adjustable; that the device as a whole may, if desired, be mounted on wheeled axles, and that said axles may be straight, dropped, or hinged, as preferred, 5 and that instead of the arrangement of the power-transmitting parts shown in the drawings any suitable power-transmitting device or devices which will accomplish the desired result may be substituted therefor. Again, 10 it is obvious that a flexible or foldable hood or continuation of the feed-casing C may be employed, if desired, to connect the open end of the conveyer-passage with the opening in the elevator-boot and that the flexible or 15 foldable continuation of the forced-feed passage may be secured either to the elevator-boot or the casing C in any suitable manner. It is also obvious that the number, size, and 20 form of the parts of my device may be greatly varied without departing from the principle of the invention.

I claim as my invention—

1. In an elevator the combination of a vertically-arranged elevating means, a relatively 25 practically horizontally arranged feed means in communication at one end with said vertically-arranged elevating means, and having its opposite end horizontally movable, and an independently horizontally adjustable receiving member carried by the horizontally-movable end of the said feed means, substantially as described.

2. In an elevator the combination of an elevating means, a feed means having one end 35 in communication with the said elevating means and its opposite end horizontally movable in respect thereto, and an independently horizontally adjustable receiving member mounted upon the movable end of the said 40 feeding means, substantially as described.

3. In an elevator, the combination of elevating means, feed means horizontally adjustable with relation to said elevating means, a hopper mounted upon the casing of said 45 feed means, and means whereby said hopper will be independently horizontally adjustable thereupon, substantially as described.

4. The combination, with a frame, of a vertically-arranged elevating device mounted 50 therein, a boot provided at the lower end of said elevating device, a horizontal feed device hinged near said boot and arranged to deliver the material to be elevated thereto, said horizontal feed device having a limited 55 lateral movement to permit the material to be fed to said boot from different directions, and a hopper device provided on said horizontal feed device.

5. The combination, with a suitable frame, 60 of an upright casing mounted therein, an elevating device provided within said casing, a boot provided at the lower end of said casing, a horizontally-swinging casing hinged on said frame, a feed device operating within said 65 horizontal casing, and a hopper provided on said horizontal casing.

6. The combination, with a frame, of an up-

right elevator-casing supported therein, an elevating device provided in said casing, a substantially horizontal casing arranged near 70 the ground-line and having its inner end hinged near the lower receiving end of said upright casing and arranged to deliver material to said lower end and to be swung horizontally to an inoperative position beside said 75 frame, a feed device operating in said horizontal casing, and a hopper provided on said horizontal casing.

7. The combination, with a frame, of an upright casing mounted therein, an elevating 80 device provided within said casing, a boot arranged at the lower end of said casing, a horizontal casing hinged on said frame and having its inner end when in its operative position contiguous to said boot, means for locking said horizontal casing when in said operative position, said horizontal casing being arranged when unlocked to be swung around to one side against said frame into an inoperative position, a feed device operating within 90 said horizontal casing, and a hopper provided on the outer end of said horizontal casing.

8. The combination, with a portable frame, of an upright elevator-casing hinged thereon and arranged to be swung down to a substantially horizontal position, an elevating device operating within said casing, a horizontal casing hinged on said frame and projecting rearwardly therefrom and having its inner end when in its operative position contiguous to 100 the lower end of said upright casing to deliver the material to be elevated thereto but adapted to be swung around horizontally to an inoperative position beside said frame away from said elevating device, a feed device operating within said horizontal casing, and a receiving member provided on said horizontal casing.

9. The combination, with a suitable frame, of an upright casing mounted therein, an elevating device operating within said casing, a boot provided at the lower end of said casing, a horizontal casing, lugs provided on said frame on each side of said horizontal casing, brackets provided on said horizontal casing, rods passing through said brackets and said lugs and supporting the outer end of said horizontal casing and normally preventing lateral movement of the same but permitting it to be swung to one side on one 115 rod when the other rod is removed, a feed device operating within said horizontal casing, and a hopper provided on the outer end 120 of said horizontal casing.

10. The combination, with an axle, of a 125 frame mounted thereon, an upright elevator-casing hinged on said frame and adapted to be swung down to a substantially horizontal position thereon, an elevating device operating within said casing, a horizontal casing 130 hinged on said frame near its inner end and having a lateral swinging movement partially around the lower end of said upright casing, the inner end of said horizontal casing being

near the lower end of said upright casing, means for locking said horizontal casing, a feed device operating within said horizontal casing, and a hopper provided on said horizontal casing.

11. The combination, with an axle, of a frame mounted thereon, an upright casing hinged on said frame and arranged to be swung down to a substantially horizontal position thereon, an elevating device provided within said casing, a boot provided at the lower end of said casing, a horizontal casing supported on said frame near the ground-line, the inner end of said horizontal casing being contiguous to said boot, a feed device operating within said horizontal casing, and a receiving member provided on the outer end of said horizontal casing.

12. The combination, with the forward and rear axles, of a frame mounted on said rear axle, an upright elevator-casing hinged on said frame above said rear axle and arranged to be swung down to a substantially horizontal position thereon, and elevating device operating within said casing, a boot provided at the lower end of said casing, a rearwardly extending horizontal casing having its discharge end near said boot, a feed device op-

erating within said horizontal casing, a power mechanism supported on the forward axle, and operative connections provided between said power mechanism and said elevating and feed devices, substantially as described.

13. The combination, with a rear axle and the standards supported thereon, of an upright elevator-casing hinged on said standards and arranged to be swung forward to a substantially horizontal position thereon, an elevating device operating within said casing, a horizontal casing hinged on said frame and arranged to be swung horizontally to an operative position to deliver material to said upright casing or to an inoperative position at the side of said frame, a feed device operating within said horizontal casing, a receiving member, a forward axle, a power mechanism supported thereon, and operative connections provided between said power mechanism and said elevating and feed devices, substantially as described.

In witness whereof I have hereunto set my hand this 17th day of June, 1903.

JOHN F. SANDERSON.

In presence of—

PAUL MACGUFFIN,
EDWARD H. SMITH.
